UNITED STATES PATENT OFFICE.

AUGUST DINKLAGE, OF EAST ORANGE, NEW JERSEY.

RAIL ANCHOR.

Application filed February 6, 1923. Serial No. 617,303.

To all whom it may concern:

Be it known that I, AUGUST DINKLAGE, a citizen of the United States, and a resident of East Orange, county of Essex, and 5 State of New Jersey, have invented certain new and useful Improvements in Rail Anchors, of which the following is a specification.

This invention relates to anchoring devices and has more special reference to anchoring devices for preventing the creep of railway track rails.

One of the factors affecting the effectiveness of rail checks is the expansion and contraction of the rail due to temperature changes. In the type of rail check comprising a wedging member, the expansion of the rail tends to tighten the check parts and to ordinarily promote the effectiveness of the 15 check, whereas the contraction of the rail under circumstances preventing a free movement of the parts often causes such a loosening of the check parts as to render the check ineffective to accomplish its designed purpose. In this type of check, the wedge member is often held relatively stationary to the movement of the rail by ice, track ballast or other extraneous material and is withdrawn from its locking position in the check 20 device on contraction of the rail.

One phase of the present invention resides in the provision of a rail check construction in which the check parts under ordinary operating conditions retain their initially assembled relation. More specifically stated, the structure comprehends a yoke and a 25 wedging member, the wedge being movable as to the yoke only in an angularly inclined direction with respect to the longitudinal axis of the rail held by the yoke, so that the normal movement of the yoke and rail differs from the direction in which the wedge may be normally withdrawn from the yoke.

Another phase of the invention resides in the provision of a yoke having ends adapted to engage and substantially fit opposite sides of the rail so as to facilitate maintenance of the yoke at a proper angle 40 to the longitudinal axis of the rail during the initial positioning operation. The fit of the opposite ends also tends to prevent rotation of the yoke due to the rotational pressure exerted by the angularly inclined wedge 45 on contraction of the rail.

Another phase of the present invention

resides in the provision of a wedge and yoke arranged to cooperate with each other in such a manner that they cannot be incorrectly assembled and take positions of maximum contact with the rail and each other. More specifically stated this effect is accomplished by providing a tapered recess in the yoke and a correspondingly tapered part on the wedge which is adapted 60 to enter the yoke recess, the taper being arranged so that the wedge surface is in contact with the rail base and the yoke is maintained in such position that the full contact of the ends is utilized.

While one embodiment of the invention is illustrated in the drawing, it is to be understood that this embodiment merely serves as an illustration of the underlying principles of the invention so that they 70 may be readily comprehended by those skilled in the art and is not intended as limiting the invention to the specific form disclosed therein.

In said drawings:

Fig. 1 is a side elevation of the invention as applied to a track rail.

Fig. 2 is a top plan view of the invention partly shown by dotted lines.

Fig. 3 is a section of Fig. 1 on the line 85 3—3.

Fig. 4 is a fragmentary section of some of the elements and

Fig. 5 is a detail view of one of the elements of the invention.

Continuing now by way of a more detailed description of the invention, a track rail A is located on a road bed part—specifically a tie B—in the customary manner. A shoe or yoke C comprises a pair of oppositely disposed inturned ends C' preferably symmetrically arranged on each side of the yoke center and each having a rail base fitting shoulder or recess C''. The recesses C'' afford means for accurately guiding the yoke 90 when being initially driven to an operative position and prevent rotational movement of the yoke on the rail when the rail is seated in said recesses. The ends C' are inturned 95 in such a manner as to provide clearance below the recess so that when one edge of the rail base is passed into this clearance the opposite edge of the rail base will pass the oppositely disposed end C', the recesses C'' being so disposed that they snugly fit the 100 rail base when the latter is in operative position.

In order to maintain the rail base in said recesses and to cause the yoke ends to bear firmly on the rail base edges and hold the yoke in locked position therewith, a wedging member D is inserted between the yoke and rail. In order that this wedge may be held in properly aligned position, a wedge receiving recess E is arranged in the yoke C, the material of the yoke being preferably offset or bowed in the manner shown to afford the requisite strength to the yoke. To accommodate the tapered part or rib G of the wedge, the recess E is tapered and in order that the yoke C may not be tilted from its normal position when the wedge is driven home and thus leave but a portion of the yoke ends C in effective frictional contact with the rail base, the taper of the recess and wedge part correspond to each other. The recess E and wedge part G are preferably conical to permit the wedge to rotate about its longitudinal axis and to take a position of maximum bearing effectiveness against the rail base; although the present invention is not limited to any particular shape wedge part or recess.

Inasmuch as the movement of the rail takes place along its longitudinal axis, the yoke in accompanying the moving rail part, also moves in a direction parallel to the rail axis. In order to prevent separation of the wedge and yoke on movement of the latter, the wedge part receiving recess E' is angularly arranged with respect to the length of the rail so that the normal direction for withdrawal and insertion of the wedge differs from the normal direction of rail and yoke movement. In this manner, unless the resultant of the component forces acting on the wedge should be in a direction corresponding to the normal direction of its withdrawal from the yoke, the wedge necessarily must accompany the yoke and under ordinary circumstances free itself of, or tear through any of the materials ordinarily obstructing the movement of the wedge, and which would in fact separate the wedge from the yoke in the devices heretofore in use. To afford a substantial footing against the tie for the check device, one end of the wedge D has a depending apron or flange J, the abutting face of which is generally angularly inclined with reference to the direction of withdrawal of the wedge or in other words is parallel to the tie face. The wedge part receiving recess E' and the wedge part G may be corrugated or roughened as indicated in the drawings, although a smooth recess and wedge part are, of course, included in the scope of the invention.

In locating the device in operative position, one of the yoke ends C' is passed over one of the rail base edges, the rail edge being permitted to take a position within the inturned end C' below the recess C''. In

this position the opposite end C' will clear the opposite rail edge. The rail edges may then be located in the recesses C'' by appropriately shifting the yoke C and the latter may then be moved to a position where the wedge D having its flange J abutting against the tie, loosely enters the recess E between the yoke and rail base. By evenly driving the yoke C "home" on the wedge D the device tightens up and securely anchors the rail. During the "tightening up" of the device parts, the apron or flange J moves laterally across the face of tie B until the parts are fully tightened. The thrusts of the rail cause this apron to become slightly embedded in the tie and thus prevented from moving laterally. Inasmuch as the flange J can only move in a direction parallel to the direction of rail movement it necessarily must either break or tear through any obstructing material.

While various equivalents and equivalent modifications are mentioned in the foregoing specification, it is to be understood that these are not the only equivalents which may be used and are only inserted for the purpose of affording a clear understanding of the principles of the invention.

It is claimed:

1. The combination with a track rail and a road bed part, of means to check the creep of the rail, said means comprising a wedging member, one end of which is adapted to abut against the road bed part, and which when in operative position is angularly located with respect to the direction of rail movement and is free to move with the rail.

2. The combination with a track rail and a road bed part, of means to check the creep of the rail, said means comprising a plurality of cooperating members one of which embraces the rail base and which is clamped downwardly against the rail base by the other member when the latter is in operative position, the last named member being held by the rail embracing member in an angularly inclined position with respect to the direction of rail movement and one of its ends being adapted to abut against the road bed part.

3. The combination with a track rail and a road bed part, of means to check the creep of the rail, said means comprising a yoke and a wedge, the wedge being adapted to be inserted between the yoke and the rail to clamp the yoke downwardly against the rail base, the yoke having a wedge receiving recess underlying the rail base so disposed that the direction of withdrawal of the wedge differs from the direction of rail movement, the wedge being adapted to accompany the yoke on movement of the latter.

4. The combination with a track rail and

- 5 a road bed part, of means to check the creep of the rail, said means being adapted to move with the rail comprising a tapered member, one end of which is adapted to abut against the road bed part and which is angularly disposed with respect to the direction of the rail movement.
- 10 5. The combination with a track rail and a road bed part, of means to check the creep of the rail, said means comprising a rail engaging member and a tie abutting wedge, the tie abutting member being angularly held with respect to the direction of the rail movement by the rail engaging member.
- 15 6. The combination with a track rail base and a road bed part, of means to check the creep of the rail, said means comprising a yoke having a recess adapted to engage the rail base and a wedge fitting said recess and underlying the base to lock the yoke to the rail, the wedge when in operative position being held in said recess at an angle to the direction of the rail movement and being unattached to the road bed part.
- 20 7. The combination with a track rail and a road bed part, of means to check the creep of the rail, said means comprising a yoke adapted to engage the rail base and having a tapered recess, and a wedge which is snugly fitted in the recess and is inseparable from the yoke when in operative position by the contraction of the rail.
- 25 8. The combination with a track rail and a road bed part, of means to check the creep of the rail, said means comprising a yoke adapted to engage the rail base substantially at right angles thereto and having a wedge receiving recess angularly inclined with respect to the longitudinal axis of the rail and located below the rail base.
- 30 9. The combination with a track rail and a road bed part, of means to check the creep of the rail, said means comprising a yoke having oppositely disposed inturned ends each of which has a recess adapted to fit opposite rail edges and means to force the yoke recesses downwardly against the rail edges.
- 35 40 10. The combination with a track rail and a road bed part, of means to check the creep of the rail, said means comprising a yoke having a tapered recess and guide recesses to receive the rail and prevent rotation of the yoke with respect to the rail.
- 45 50 11. The combination with a track rail and a road bed part, of means to check the creep of the rail, said means comprising a yoke having a tapered recess and guide recesses to receive the rail and a wedge having a correspondingly tapered part to fit said recess.
- 55 60 12. The combination with a track rail and a road bed part, of means to check the creep of the rail, said means comprising a yoke adapted to engage the rail base at right angles thereto and having a tapered recess, and a wedge having a correspondingly tapered part to fit said recess, the recess being angularly inclined with respect to the longitudinal axis of the rail.
- 65 70 13. A wedge member for creep checks comprising a substantially flat portion adapted to underlie the rail base, the flat portion having a tapered wedging part circular in cross section and a biased tie abutting end.
- 75 14. The combination of a track rail and a wedging member adapted to move with the rail in one direction underlying the track rail base, the wedging member having a biased tie abutting end.
- 80 15. A yoke for rail creep checks comprising oppositely disposed ends and having a recess angularly inclined with respect to a perpendicular to the plane of the yoke, the recess being substantially centrally located between the ends.
- 85 16. A yoke for rail creep checks comprising oppositely disposed inturned ends each having a recess adapted to fit the rail edges.
- 90 17. A yoke for rail creep checks comprising a single bar having oppositely disposed inturned ends each of which has a recess adapted to fit the rail edges.
- 95 18. A yoke for rail creep checks comprising oppositely disposed symmetrical ends having rail receiving recesses shaped to fit the rail edge and a tapered wedge receiving recess.
- 100 19. The combination with a track rail and road bed part, a yoke having ends adapted to engage and fit the rail, and having a recess angularly inclined with respect to the longitudinal axis of the rail, and a wedge part adapted to engage said recess and abut against the road bed part, the fitted yoke ends preventing any turning movement of the yoke by the pressure exerted by the wedge in the yoke recess.
- 105 20. The combination with a track rail and a road bed part, of a yoke having a recess which is tapered downwardly away from the plane of the rail base and a wedge part adapted to fit said recess, the taper of the recess and the wedge part being similar so that the wedge takes a position of maximum efficiency with respect to the rail base the yoke having means to prevent its rotation with respect to the rail.
- 110 21. A creep check device for track rails comprising a rigid wedging member and a cooperating rail holding member having means comprising a wedge receiving recess to hold the wedging member in locked engagement therewith on contraction of the rail.
- 115 22. A creep check device for track rails consisting solely of a yoke and a wedging
- 120
- 125
- 130

member, the members being mutually fitted to prevent incorrect assembling, and the wedging member being inclined with respect to the direction of rail movement.

5 23. A creep check device for track rails comprising a yoke and a wedge cooperating with the yoke and snugly fitted thereto and means on said wedge and yoke for permitting said wedge to rock transversely of the 10 yoke, the parts being adapted to be assembled without changing the configuration of the parts.

15 24. A creep check comprising a yoke having oppositely disposed inturned ends, each of the ends having a recess adapted to receive and fit the rail edge and means to force and hold the rail edges in said recesses.

20 25. A creep check comprising a yoke and a wedge, the latter being adapted to abut against a part of the road bed, to move relatively thereto and to force the yoke down-

wardly against the rail, the direction of withdrawal of the wedge differing from the direction of rail contraction.

25

26. A yoke for creep checks comprising a single bar having oppositely disposed in-turned ends, each of which has a recess adapted to receive and fit the rail edge and an offset portion to form a recess adapted to receive a wedge.

30

27. A creep check comprising a yoke having a wedge receiving recess and a tie abutting wedge, the yoke having inturned ends shaped to fit the rail edges, the space between the edges corresponding to the width of the rail base, and the wedge fitting in the recess and being held thereby in a direction inclined to the direction of rail movement.

35

Signed at the city of New York, in the county of New York and State of New York, this 24th day of January, 1923.
